CLAIM

The ornamental design for a tri-fold vanity mirror, as shown and described.

DESCRIPTION

FIG. 1 is a front perspective view of a tri-fold vanity mirror according to the claimed design.

FIG. 2 is a right side elevation view thereof, the left side elevation view being a mirror image of the right side elevation view.

FIG. 3 is a front elevation view thereof.

FIG. 4 is a rear elevation view thereof.

FIG. 5 is a top plan view thereof.

FIG. 6 is a bottom plan view thereof.

FIG. 7 is a front perspective view of the mirror of FIGS. 1-6, showing the mirror in a first alternate position.

FIG. 8 is a right side elevation view thereof, the left side elevation view being a mirror image of the right side elevation view.

FIG. 9 is a front elevation view thereof.

FIG. 10 is a rear elevation view thereof.

FIG. 11 is a top plan view thereof.

FIG. 12 is a bottom plan view thereof.

FIG. 13 is a front perspective view of the mirror of FIGS. 1-6, in a second alternate position.

FIG. 14 is a right side elevation view thereof, the left side elevation view being a mirror image of the right side elevation view.

FIG. 15 is a front elevation view thereof.

FIG. 16 is a rear elevation view thereof.

FIG. 17 is a top plan view thereof; and,

FIG. 18 is a bottom plan view thereof.

The broken lines showing images in the tri-fold vanity mirror are included for the purpose of illustrating environmental subject matter and form no part of the claimed design.

The areas of the tri-fold vanity mirror bounded by broken lines form no part of the claimed design.
